Andam L. Mott, New York City

Letters Patent

The Schedule referred to in these Letters Patent and making part of the same containing a description in the words of the said Andam L. Mott himself of his improvement in Stoves.

To all to whom these presents shall come, I, A. L. Mott, do witness that I, for Andam L. Mott, of the City and State of New York, have invented and applied to use a new and useful improvement in Stoves in which the advantages of that peculiar kind of Stove called open Franklin are combined with the advantages of close Stoves, and that the following is, a full and exact description of the said new kind of Stove, as invented and improved by me.

The Stove as made by me is a parallelopiped or rather a prism of approximately of any required dimensions, resting on a horizontal plate and having the lower part of its sides open to any suitable height with places projecting on the right and left of the sides so left open and placing the fire wood in a Franklin. This forms the front of the Stove, a grate with bars standing perpendicular and bending recumbently at their outer ends so placed near the bottom of the Stove, and with the front or perpendicular part of the grate about equally distant from the front and back part of the Stove. A plate or other plate, called a fire back, distance above the top of the grate in a position inclining upwards to the front of the Stove, and join closely to the top of the front part of the parallelopiped. Thus the Stove presents in its front the appearance of an open Franklin, for about one half its height and above that is a close Stove. Through the middle of the close part of the Stove and near its grate on a line with front of the grate, a partition placed vertically divides the front part from the back part of the Stove. The part which may be open towards a fire kind of coal or turf &c. is placed in the front division and having for its bottom an inclined plane it falls gradually into the grate and as the draft is through the back of the grate is to a close stove it burns when ignited similar to open fire. The form and appearance of this

[Handwritten text: "Drawn & engraved by J. C. Smith"]

above described Stone will be manifestly apparent on an inspection of the model, and the drawings deposited by me in the Patent Office, Washington.

The drawing marked A presents in perspective a view of the front of the Stone, showing the grate, the flueing pipes, the Franklin part of the Stone, the two connecting plates, one of them marked "J. H. Melt Patent" On the top of the Stone are two small rods placed for a handle in the top, the one leading into the front division of the body of the Stone, serves for the introduction of the fuel with which the division of the stone may be filled as often as necessary. The other connects an aperture over which a cover may be placed for holding water etc. On this drawing a flue is shown extending perpendicular to the front, to which the pipe of the flue is affixed, this part however is chiefly for ornament.

The drawing marked B is a sectional view through the middle of the Stone at right angles with the front. It shows the position of the grate and the pipes of the back, and the mode adopted by me for increasing the flue of the Franklin part of the Stone, having separate flueing pipes attached to the body of the Stone, or also the partition (made of soap stone), which separates the body of the Stone horizontally into two divisions. The one division marked A containing the fire, the other marked B being the fire.

The middle flue of the Franklin part of the Stone may be of any desired size, and the grate by being placed at a greater or less distance from the back of the stone may be rendered more or less impervious, and the connecting plate or plates may be either more or less inclined. The chief object designed to be effected by the connecting plate or plates is to cause the draft to be through the body of the stone or rather through the middle of the rear part of the Stone, which would not be the case if the grate was placed in the front. The connecting plate or plates may be made of a form somewhat circular which will not only improve the appearance of the front of the Stone but also aid in throwing the draft to the middle of the stone. The position of the grate as described above causes the heat to be distributed by radiation in the Franklin part of the stone and distributed through the connecting plate. It is not necessary in ordinary cases to line the parts immediately adjacent to the fire. — These however may be done and also

small pieces may be attached to or near the ends of the grates to protect the sides of the stove. The partitions in the upper or close part of the stove may be omitted but in that case many although by no means all the advantages of the stove as described will not be gained. The stove will be made of any material that will resist the action of fire and in a great variety of forms - That which I now claim is the above described.

That as improved by me is the combining the open back door with the close door by connecting the grate which is thrown back by a plate or plate with the close part of the stove - the one stove being thus placed so it will be above or higher than the other October 31 1863
